UNITED STATES PATENT OFFICE.

SAMUEL J. MARSH, OF QUESNEL, BRITISH COLUMBIA, CANADA.

DEVICE FOR SAVING GOLD AND OTHER PRECIOUS METALS.

Application filed July 1, 1920. Serial No. 393,366.

To all whom it may concern:

Be it known that I, SAMUEL J. MARSH, citizen of the United States, residing at Quesnel, in the Province of British Columbia, 5 Canada, have invented certain new and useful Improvements in Devices for Saving Gold and Other Precious Metals, of which the following is a specification.

This invention relates to a method and 10 means for recovering fine gold existing in a free state in alluvial deposits or in the pulp resulting from crushing alluvial concentrates or free gold ores.

The method is also adapted to receive a 15 considerable proportion of the fine flakes and grains of platinum and osmiridium which are frequently associated in such gold bearing ores.

The object of the invention is to make 20 as full a recovery as possible of such free gold by amalgamation and to recover fine flour gold not readily recoverable by such means and therefore frequently lost.

It is obvious that when the metallic 25 particles are contained or included in the grains of concentrates or ores, such concentrates or ore must be crushed or ground very fine to liberate the particles.

The invention is particularly described in 30 the following specification, reference being made to the drawings by which it is accompanied, in which:

Fig. 1 is a longitudinal section of the 35 amalgamator being taken on the line 1—1 in Fig. 2.

Fig. 2 is a plan of the same.

Fig. 3 is a longitudinal section of the riffle frame to an enlarged scale.

Fig. 4 is a cross section on the line 4—4 in 40 Fig. 1.

Fig. 5 is an end view of the base frame showing the connection of the intermediate frame to it.

In these drawings 2 represents the base 45 frame from an upward projection at one end of which a pivot 3 supports a sub-frame 4 at an angle of approximately thirty degrees. The lower ends of this sub-frame 4 rest on wedges 5 by which the angle of the 50 frame may be adjusted to meet requirements. From this sub-frame 4 a table frame 6 is carried on upright springs 7, the ends of which are socketed in the sub-frame and table frame respectively. These springs are 55 adapted to allow for lateral oscillation of

the table frame, which oscillation is imparted by eccentrics 8 secured on a shaft 9 rotatably mounted parallel to the table frame and driven by a belt over a pulley 10 from any convenient source of power.

Across the table frame 6 transverse bars 11 are secured at substantially uniform distances apart, the upper sides of which bars are angled to the frame so as to be practically level.

The riffle frames 12 are inserted through slotted apertures 15 in the side walls 16 of the table frame 6, in which they are supported and are retained therein by any suitable simple fastening, such as a pivoted 70 elongated button.

On the upper side of each transverse bar 11 an amalgamated plate 13 is secured and on the upper sides of the riffle bars 12 a thick woolen blanket 14 is secured, the 75 upper sides of the bars being rounded to receive it, and the blanket is loosely pocketed between the bars as shown in Fig. 3.

At the upper end of the table suitable provision is made at 17 for distributing the 80 pulp evenly over the width of the table and at the lower end provision is made for receiving the tailings.

In use, the pulp with a sufficiency of water is delivered and distributed at 17, a little 85 quicksilver being sprinkled at intervals over the spread pulp and over the riffle blankets. This spread pulp flows successively over the substantially level amalgamated plates 13 and the blanket pockets of the riffle 90 frames 12.

Any free gold that may under the flow and the lateral vibration be brought into contact with the amalgamated plates 13 will adhere thereto, while rusty gold and platinum or other precious metals, which have no affinity for quicksilver, will be caught in the blanket riffles of 14, which riffles alternate in groups with the amalgamating plates. Any free gold that may escape the amalgamating 100 plates will also be caught in the riffles and amalgamate with the sprinkled quicksilver.

An essential feature of this gold recovery means lies in the relatively steep angle at which the riffle frames are set, an angle of 105 forty-five degrees in these as against a usual grade not exceeding one in twelve (almost 5°). This steep angle is such that the water and pulp as it falls from one riffle to the other will be aerated or will bubble in its 110

fall. This bubbling of the water prevents the individual fibres of the wool from being laid down but keeps them erect and in a state of agitation which is the most favorable condition for the entanglement of fine particles of metal. Beyond this is the fact that the fine float particles of metal are attracted and attach themselves to the surfaces of the air bubbles and as these bubbles are carried down among the fibres of the blanket they burst and the collected particles of fine gold are retained in contact with the blanket, and if subject to amalgamation will agglomerate with the quicksilver which has been sprinkled among the pulp and settled in the bottom of the riffles.

Another important feature of construction lies in the provision by which the riffle frames 12 may be removed and replaced without stopping the machine or interrupting the process. The button which retains the frames 12 in position in the side walls 6 being released, a fresh riffle frame is placed against the end of the one in position and is pushed through while the charged frame is received on the opposite side by an attendant.

In the steeply pitched frames of deeply pocketed blanket covered riffles alternating with transversely disposed substantially horizontal amalgamated plates, this device marks a distinct improvement in appliances for the recovery of fine gold or other rare metals, such as platinum and osmiridium, all of which may be recovered in the one machine. It is applicable either for the recovery of fine gold from placer dirt or from crushed ores or concentrates of ores which contain finely divided precious metals included in the crystalline structure of the ore and set free by the crushing.

Having now particularly described my invention, I hereby declare that what I claim as new and desire to be protected in by Letters Patent, is:

1. Means for obtaining precious metals from ore pulp, said means comprising a launder having relatively deep blanket covered riffles across its width, the general grade of the riffled portions of the launder being not less than twenty degrees from the

horizontal, and means for spreading the finely divided pulp with water across the width of the launder at the upper end.

2. Means for obtaining precious metals from ore pulp, said means comprising a launder, amalgamated plates at intervals apart across the bottom of said launder, groups of relatively deep blanket covered riffles across the width of the launder between the amalgamated plates, the amalgamating plates being set at a slight angle from the horizontal and the general grade of the riffle groups being at an incline of not less than twenty degrees from the horizontal.

3. Means for obtaining precious metals from ore pulp, said means comprising a launder, frames of relatively deep blanket covered riffles inserted across the width of the launder the ends of the riffle frames being inserted in apertures in the sides of the launder to be coincident therewith when in place.

4. Means for obtaining precious metals from ore pulp, said means comprising a launder, amalgamated plates in the bottom of it across the width at intervals apart lengthwise of the launder, said plates being at a slight incline from the horizontal, frames of relatively deep blanket covered riffles inserted through apertures in the side walls of the launder to extend across it between the amalgamated plates, the ends of the riffle frames being coincident with the side walls of the launder, and the general slope of the riffles being not less than twenty degrees.

5. Means for obtaining precious metals from ore pulp, said means comprising a base frame, an intermediate frame pivotally connected at one end to the base frame and adjustably supported at the other end therefrom, a launder supported from the intermediate frame on springs that will permit of lateral vibration being imparted to the launder, and means mounted on the intermediate frame for imparting a lateral vibrating movement to the launder.

In testimony whereof I affix my signature.

SAMUEL J. MARSH.
